UNITED STATES PATENT OFFICE.

EDWIN H. WATERBURY, OF STAMFORD, CONNECTICUT.

TRIANGLE.

SPECIFICATION forming part of Letters Patent No. 660,406, dated October 23, 1900.

Application filed April 3, 1900. Serial No. 11,343. (No model.)

To all whom it may concern:

Be it known that I, EDWIN H. WATERBURY, a citizen of the United States, and a resident of Stamford, in the county of Fairfield and State of Connecticut, have invented a new and Improved Triangle, of which the following is a full, clear, and exact description.

This invention relates to improvements in triangles; and the object is to provide a triangle of simple and comparatively inexpensive construction that may be readily adjusted to any desired angle for batter-slopes, roof-pitches, degrees, &c., and so arranged that it will lie flat upon the paper.

I will describe a triangle embodying my invention and then point out the novel features in the appended claims.

Reference is to be had to the accompanying drawings, forming a part of this specification, in which similar characters of reference indicate corresponding parts in all the figures.

Figure 1 is a plan view of a triangle embodying my invention. Fig. 2 is an end view. Fig. 3 is a section on the line 3 3 of Fig. 1. Fig. 4 is a perspective view showing a sliding washer construction. Fig. 5 is a section on the line 5 5 of Fig. 1, and Fig. 6 is a section on the line 6 6 of Fig. 1.

Referring to the drawings, 10 designates the base of the triangle and which may be provided on its upper side with any desired scale for measurement of angles. Movable relatively to the base are the pitch-line rules 11 and 12, hinged together at their adjacent ends, as at 13. The ends of these rules 11 and 12 extend underneath the base 10, as shown in Fig. 1, and, as plainly indicated in Figs. 4 and 5, the under side of said base-rule is recessed, so that the under sides of the rules 11 and 12 will be flush with or on a plane with the portion of the base that rests upon the paper. Screws 14 pass through the ends of the rule-sections 11 and 12, and thence through washers 15 and 16, the washer 16 being provided with blocks 17 on the under side engaging in slots 18, formed in the base. Thumb-nuts 19 engage with the screws for

the purpose of tightening the rule-sections 11 and 12 as adjusted.

The rule-sections 11 and 12 are held from vibration by means of braces 20 and 21, pivotally connected at their adjacent ends to the base 10 and having their outer ends pivotally connected to said rule-sections, as plainly indicated in the drawings. It will be noted that the heads of the screws 14 are countersunk or seated in the rule-sections, so that the outer surfaces of said heads are on a plane with the under sides of the sections, thus permitting the whole device to lie closely upon the paper.

In operation when it is desired to adjust the angles the thumb-nuts 19 are to be loosened. Then the rule-sections may be moved relatively to the base, the block portions 17 of the washers 16 permitting of a free movement.

Having thus described my invention, I claim as new and desire to secure by Letters Patent—

1. A triangle, comprising a longitudinally-slotted base-rule, angle-rules pivotally connected together, set-screws engaging with said angle-rules and passing through the slots in the base, and braces pivotally connected to the base and to the angle-rules, substantially as specified.

2. In a triangle, a longitudinally-slotted base-rule, angle-rules pivotally connected together, washers having block portions extended into the slots in the base-rule, screws passing through said washers and engaging with the angle-rules, thumb-nuts on the screws, and braces pivoted at one end to the base-rule and at the other end to the angle-rules, substantially as specified.

In testimony whereof I have signed my name to this specification in the presence of two subscribing witnesses.

EDWIN H. WATERBURY.
